Primary Examiner — Deanna L Pratt(57) CLAIM

The ornamental design for a bathroom mirror, as shown and described.

DESCRIPTION

FIG. 1 is a perspective view of a first embodiment of a bathroom mirror showing my new design;
 FIG. 2 is another perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof;
 FIG. 8 is a bottom plan view thereof;
 FIG. 9 is an enlarge view of portion 9 shown in FIG. 1;
 FIG. 10 is an enlarge view of portion 10 shown in FIG. 2;
 FIG. 11 is a perspective view of a second embodiment of the bathroom mirror showing my new design;
 FIG. 12 is another perspective view thereof;
 FIG. 13 is a front elevational view thereof;
 FIG. 14 is a rear elevational view thereof;
 FIG. 15 is a left side elevational view thereof;
 FIG. 16 is a right side elevational view thereof;
 FIG. 17 is a top plan view thereof;
 FIG. 18 is a bottom plan view thereof;
 FIG. 19 is an enlarge view of portion 9 shown in FIG. 11; and,
 FIG. 20 is an enlarge view of portion 10 shown in FIG. 12. The broken lines in the drawings depict portions of the bathroom mirror that form no part of the claimed design.

1 Claim, 20 Drawing Sheets(56)
